Patented Apr. 18, 1916.

UNITED STATES PATENT OFFICE.

CURTIS STEPHENS, OF DICKERSON RUN, PENNSYLVANIA.

WRENCH.

1,179,574.

Specification of Letters Patent. Patented Apr. 18, 1916.

Application filed January 21, 1915. Serial No. 3,431.

To all whom it may concern:

Be it known that I, CURTIS STEPHENS, a citizen of the United States, residing at Dickerson Run, in the county of Fayette 5 and State of Pennsylvania, have invented certain new and useful Improvements in Wrenches, of which the following is a specification.

This invention relates to wrenches, and 10 more particularly to that type of wrench in which one of the jaws slides relatively to the other jaw for the purpose of obtaining different adjustments.

The invention has for one of its objects 15 to provide a wrench in which the adjustments are easily and quickly attained.

A further object of the invention is to provide a wrench in which the jaws will be positively held in adjusted position during 20 the operation of the wrench.

Referring to the drawings; Figure 1 is a view in side elevation of a wrench constructed in accordance with the present invention and with the side plate removed; 25 Fig. 2 is a transverse sectional view of the sliding jaw taken on the line 2—2 of Fig. 1; Fig. 3 is a longitudinal sectional view taken on line 3—3 Fig. 1 of the sliding jaw showing the method of mounting the sliding locking block; Fig. 4 is a detail view 30 of the means employed for operating the sliding locking block, and Fig. 5 is a detail view of the cover plate.

Referring more particularly to the drawings, the reference numeral 1 designates the shank of the wrench, 2 the stationary jaw 35 rigidly secured to one end thereof and 3 the handle which is rigidly attached to the opposite end.

40 A portion of the shank 1 is squared as at 4, and slidably mounted on the said squared portion is a jaw 5. One of the faces of the squared portion is formed with a rack 6 throughout a portion of its length as shown 45 in Fig. 1.

To provide for sliding relation of the jaw 5 with the shank 1, the jaw 5 is provided with two spaced yokes 7 and 8 which surround the said squared portion of the shank 50 1. The yokes 7 and 8 are substantially L-shaped, the jaw being secured in place on the shank 2 by means of the removable plate 9.

The sliding jaw 5 is provided with a recess or cut out portion 10, the top wall of 55 which near the rear end thereof is inclined

downwardly as at 11 for a purpose to be hereinafter described. The end walls 12 and 13 of the recess or cut out portion 10 are provided with slots or recesses 14, said 60 recesses terminating at a point below the top of said walls.

Slidably mounted in the recess 10 of the jaw 5 is a block 15 the lower face of which is provided with rack teeth 16 and the upper face of said block is formed with a compound cam 17, said upper face inclining upwardly from front to rear. Each end of the sliding block 15 is provided with an integral rib 18, each of which projects into 70 one of the slots or recesses 14 in the end walls of the recess 10 to form means for guiding the block within said recess 10.

Suitably secured at its ends to one side of the movable jaw 5 and extending longitudinally of the recess 10 on the outside thereof is a spring 20, which is secured intermediate of its ends to the side of the sliding block 15, and acts to resiliently support the same with its rack teeth 16 out of engagement with the teeth of the rack 6 of the shank 1.

Slidably mounted between the upper double cam face of the vertically sliding block 15 is a wedge shaped block 21 the apex 85 of which is bifurcated as at 22 to receive a handle member 23 which is secured therein by means of a pin 27. The handle member 23 projects through an opening 24 in one of the end walls of the recess 10, and has its 90 free end provided with a knob 24.

Surrounding the handle member 23 is a coil spring 25 one end of which abuts the end face of the sliding jaw 5, while the other end abuts the knob 24. The tension of the 95 spring 25 tends to force the wedge shaped member 21 to the rear of the recess 10 thus maintaining the rack 16 of the block 15 in engagement with the rack 6 of the shank.

As shown in Fig. 5 the cover plate 9 has 100 its inner face recessed as at 28 to receive the spring 20 and permit of free working of the same together with the sliding block 15.

When the parts are in the position shown in Fig. 1, and it is desired to make an adjustment, the operator exerts pressure by means of the thumb upon the knob 24 of the handle member 23, and pushes the same forwardly compressing the spring 25. Such movement of the handle member 23 forces 110 the wedge to the forward portion of the recess 10 and into engagement with the lowest

portion of the compound cam face of the block 15, and permits of the spring 20 raising the block 15 to a point where its rack teeth 16 disengage the rack teeth 6 of the shank 1 leaving the jaw free to move longitudinally of the shank 1.

When the jaw 5 has been moved to the desired position on the shank 1, the thumb is disengaged with the knob 24, and the handle 23 is moved rearwardly under the influence of the coil spring 25. The rearward movement of the handle member 23 causes the wedge shaped member 21 to ride up the double cam inclined face of the block 15 until its upper inclined face 30 engages the downwardly inclined top wall of the recess 10 when the rack teeth 16 of the sliding block 15 are forced into engagement with the rack teeth 6 of the shank 1, against the action of the spring 20.

The coil spring 25 acts to hold the parts in the above described position which maintains the teeth of the rack 16 of the block 15 in engagement with the teeth 6 of the shank 1, thus securing the jaw 5 against movement relatively to the stationary jaw 2.

From the foregoing it will be seen that I have constructed a wrench which is not only cheaply manufactured, but both easily assembled, and positive in its operation.

Copies of this patent may be obtained for five cents each, by addressing the "Commissioner of Patents, Washington, D. C."

Having thus described my invention what I claim as new, and desire to protect by Letters Patent is:

A wrench of the class described including a shank having a rigid jaw at one end, a rack formed in one edge of the shank, a jaw shiftable on said shank, and comprising a body having a recess one side edge of which opens onto the said rack, while the opposite edge is provided with a wedge face, a rack 40 engaging pawl slidably guided in the end walls of said recess, a pawl spring adapted to disengage the pawl from said rack, and means for causing said pawl to engage with the rack comprising a spring pressed finger 45 operated member having a path of movement parallel to the shank, and a camming wedge block pivotally carried by one end of said member and engaging with the wedge face of the recess, and also engaging with the 50 rear side of the pawl to force the latter into engagement with the rack on the shank against the tension of the pawl spring.

In testimony whereof I affix my signature in presence of two witnesses.

CURTIS STEPHENS.

Witnesses:

Jos. A. STRICKLES,
J. ALLEN CRAWFORD.
